United States Patent Office.

M. J. WELLMAN, OF NEW YORK, N. Y.

Letters Patent No. 64,815, dated May 14, 1867.

SHIELD FOR PROTECTING WATER-BACKS IN RANGES AND STOVES.

The Schedule referred to in these Letters Patent and making part of the same.

Be it known that I, M. J. WELLMAN, of the city, county, and State of New York, have invented certain new and useful Improvements in Protecting Water-Backs in Cooking-Ranges and other Fire-Grates; and I do hereby describe and ascertain my said improvement, referring to the accompanying drawing, in which the invention is shown in section.

It is well known that in winter great danger and inconvenience are experienced by the freezing of the pipes leading to water-backs as now arranged, and many casualties by explosion and bursting have arisen, endangering lives and causing the destruction of property thereby. My improvement is to guard against danger of this kind, and enable the domestic to make a fire for cooking, &c., at all times without risking an explosion, in the coldest weather.

The construction is as follows: The water-back *a* is made in the ordinary way, with its pipes of supply and discharge, as heretofore constructed. The grate *b* and its relative position to the water-back are also of ordinary form and position. My improvement consists in interposing between the water-back *a* and the fire-chamber formed by the grate *b*, a plate of metal, *c*, which can be brought forward into the position shown in the drawing, so as to leave an air-space between the water-back and the fire, through which the air can freely circulate, and thus prevent the water-back from becoming so heated as to produce a dangerous pressure therein. The plate *c* is made to move forward and back in any convenient way by being attached to the top plate of the range, as seen in the drawing, with a knob at *d* to move it by; or it may have an arm projecting from it backward, and affixed to the water-back, or otherwise; or it may be affixed to and form a part of the grate, which latter will then slide forward and back with it. When it is ascertained that the current of water is free and unimpeded through the water-back, the plate *c* can be slid back against it, and the water heated therein as usual. In addition to the safety thus obtained, and the convenience thereof, the guard-plate protects the water-back against burning out; and the plate itself being cheap, can readily be renewed when burnt out or injured by the heat of the fire.

Having thus fully described my improvement in protecting water-backs in ranges, &c., I claim—

The metallic plate between the water-back and the fire, and forming the back of the fire-place, and protecting the water-back at all times, so constructed and arranged as to rest against the water-back when the water-back is to be heated, and to be moved forward and permit a current of air to pass up between the said water-back and the fire when the heat of the fire is to be excluded therefrom, as and for the purposes herein set forth.

M. J. WELLMAN.
